US00D431027S

United States Patent [19]

Armstrong

[11] Patent Number: Des. 431,027

[45] Date of Patent: ** Sep. 19, 2000

[54] ELECTRICAL LOAD CONTROL MODULE

[75] Inventor: **Steven Armstrong**, Anaheim Hills, Calif.[73] Assignee: **Emhart Inc.**, Newark, Del.

[**] Term: 14 Years

[21] Appl. No.: 29/108,366

[22] Filed: Jul. 26, 1999

[51] LOC (7) Cl. 13-03

[52] U.S. Cl. D13/162

[58] Field of Search .... D13/162, 165, D13/166, 137.1, 137.3; 200/42.01, 38 FB, 38 D, 38 DA, 52 R, 51 R
